UNITED STATES PATENT OFFICE.

JOSEPH S. ISIDOR, OF NEWARK, NEW JERSEY, ASSIGNOR TO THE R. NEUMANN HARDWARE CO., A CORPORATION OF NEW JERSEY.

BAG-FRAME FASTENER.

1,324,901.

Specification of Letters Patent. Patented Dec. 16, 1919.

Application filed December 3, 1917. Serial No. 205,125.

To all whom it may concern:

Be it known that I, JOSEPH S. ISIDOR, a citizen of the United States, residing at Newark, in the county of Essex and State of New Jersey, have invented certain new and useful Improvements in Bag-Frame Fasteners; and I do hereby declare the following to be a full, clear, and exact description of the invention, such as will enable others skilled in the art to which it appertains to make and use the same, reference being had to the accompanying drawings, and to characters of reference, marked thereon, which form a part of this specification.

This invention relates, generally, to improvements in locking or holding catches for the hinged or pivotally connected frame-sections of bag-frames; and, the present invention has reference, more particularly, to a novel and simply constructed locking or holding catch for bag-frame in which the usually pivoted or hinged operating lever and the lock-post or finger are made integral, that is, from a single piece of metal, instead of being made in two pieces which are riveted together, as heretofore.

The present invention, therefore, has for its principal object to provide a neat and simply-constructed locking or holding catch comprising in combination with the shell or casing which is adapted to be secured upon one of the bag-frame sections, a pivoted or hinged lock-post or finger operating lever and a lock-post or finger forming an integral part of the said lever, but engaging the other frame-section in the usual manner, to hold the two frame-sections in their closed relation, with a view of providing a strong and a non-separating relation of the said lever and lock-post or finger, and at the same time greatly reducing the cost of construction owing to the fact that the lock-post or finger does not have to be riveted to the back of the operating lever, as heretofore.

Other objects of the present invention not at this time more particularly enumerated will be clearly understood from the following detailed description of the present invention.

The invention is clearly illustrated in the accompanying drawings, in which:

Figure 1 is a face view of a portion of a bag-frame, showing the pivotally connected frame-sections thereof, and a side elevation of a locking or holding catch made accord-

ing to and embodying the principles of the present invention; Fig. 2 is a top or plan view of the catch and a fragmentary portion of the frame-section to which it is secured; and Fig. 3 is a bottom view of the catch.

Fig. 4 is a central longitudinal vertical section of the bag-frame fastener or catch, detached from the frame-section, with the operating lever and its lock-post or finger indicated in their closed position when holding or locking the bag-frame sections in their closed relation; Fig. 5 is a similar sectional representation of the bag-frame fastener or catch, the operating lever and its lock-post or finger, however, being represented in their raised relations to permit of the separation or opening of the bag-frame sections; and Fig. 6 is a transverse vertical section of the catch, said section being taken on line 6—6 in said Fig. 5, looking in the direction of the arrow α .

Figs. 7 and 8 are central vertical sectional representations, similar to the sections represented in Figs. 4 and 5, of a bag-frame fastener or catch of a modified construction, but still made according to and embodying the principal features of the present invention.

Similar characters of reference are employed in all of the above described views, to indicate corresponding parts.

Referring now to the several figures of the drawings, the reference-characters 1 and 2 indicate portions of the usual forms of frame-sections of a bag-frame, or the like, the said frame-sections being provided with the usual leg-members 3 and 4 which are pivotally connected by means of a rivet or hinge-pin 5, substantially as shown in Fig. 1.

The complete structure of the bag-frame fastener or locking catch is indicated by the reference-character 6, and the same consists, essentially, of a suitable shell or casing which is preferably of a rectangular configuration, and comprises a flat top 7, a pair of end members 8, and the longitudinally extending sides 9. Extending downwardly from the edges of the said end-members 8 are the usual clamping lugs or projections 10 by means of which the said shell or casing is secured in its operative position upon the upper face of the said frame-section 1 in the usual manner, although it will be understood that any other fastening

means may be employed, if desired, for securing the said shell or casing in its operative position upon the said frame-section 1. At or near its one end-portion, the said shell or casing is provided in its flat top 7 with a laterally extending opening, as 11, and located at each end of the said opening are a pair of outwardly projecting bearing-positions or pintle-receiving members 12, 10 in which are suitably journaled the respective end-portions of a pin 13, said pin being arranged in and extending across the said opening 11, substantially as illustrated in the several figures of the drawings. The 15 opposite end portion of the said flat top 7 of the shell or casing is also, preferably, suitably depressed, as at 14, said top being also provided with a suitably disposed and longitudinally extending opening, as 15. 20 Suitably secured within the inner portion of the said shell or casing, preferably to the under surface of the top 7, by means of a rivet 16, or any other suitable manner, is a spring-like engaging member 17, the 25 same being made of sheet-metal having considerable stiffness, to provide a spring-member of great resiliency, said member comprising at its free end an engaging tongue or finger 18, and being also provided with 30 a longitudinally extending opening, as 19, located beneath the opening 15 with which the flat top 7 of the shell or casing is provided. Referring now to Figs. 1 to 6 inclusive, 35 it will be seen that there is suitably mounted upon the previously mentioned pin 13, the combined operating lever and lock post or finger, embodying the principal features of the present invention, the said lever being made of a flat piece of metal 20 of the 40 general configuration shown, and in its width conforming generally to the width of the flat top of the said main shell or casing. At its one end-portion, the said lever 45 is bent around the pintle 13 in the form of a hinge-member or pintle-receiving eye 21, by means of which the said lever is clamped, or otherwise mounted upon said pintle 13, the said hinge-member or eye 21 50 being usually provided with a suitably formed lug or projection, as 22, with which the tongue or finger 19 of the spring 18 is in active engagement, as will be seen from an inspection of Figs. 4 and 5 of the drawings. The main body-portion of the said lever 20 is of such length, so that when closed down upon the upper surface of the 55 said flat top 7, it will close the opening 5 in said top and will extend at its end-portion 23 sufficiently beyond the end of the said shell or casing and will thereby provide a suitable lift or finger-piece for raising and lowering the said lever, as will be evident. As shown, the metal plate of which 60 said lever is constructed is also bent under

the main body of the said plate, as at 24, said bent-under portion 25 being tightly forced against the lower surface of the said plate 20, and when the said lever is in its closed relation with the main shell or casing, said bent-under portion 24 resting directly in the depressed portion 14 of the flat top 7, as clearly indicated in Fig. 4 of the drawings. At the proper location, the undercut portion is cut away, as at 25, and terminates in a narrow extension-like member 26 which is bent at a right angle, or approximately so to the lower face of the main plate 20, said member 26 being suitably bent, as at 27, and forming a frame-section retaining or lock-post, as will be clearly evident. As shown, the said lock-post or finger extends into and is movably disposed in the openings 15 and 19 of the flat top 7 and the spring 17 for the engagement with the frame-section 2 in the manner usual to bag-frame fasteners of this character, the said lock-post or finger thus provided being preferably formed at its free end with a suitably bent projection or stop, 85 as 28, which engages the under surface of the said spring-like member 17, and serves as a stop to limit the outward movement of the operating lever 20, as will be clearly understood from an inspection of said Fig. 5 of the drawings.

In lieu of the form of combined operating lever and lock-post or finger hereinabove described, the said lever and post may be made in a manner indicated in Figs. 7 and 8 of the drawings.

The lever in this case is made of a flat piece of metal 29, its width conforming generally to that of the flat top 7 of the main shell or casing, the length of the said lever being such so that its end-portion 30, when closed, will extend beyond the end of the said shell or casing, to serve as a lift or finger piece for the purposes hereinbefore stated. At its other end the said lever is formed with a hinge-member or pintle-receiving eye, as 31, by means of which the said lever is clamped, or otherwise mounted upon the pintle 13, the said hinge-member or eye 31 being also provided with a suitably formed lug or projection, as 32, with which the tongue or finger 19 of the spring 18 is in active engagement, substantially as shown, and the purpose of which is self-evident. Integrally connected with the said hinge-member or eye 31, as shown, is a portion 33, with the end of which is integrally connected and is bent at a right angle, or approximately so, a narrow extension-like member 34 forming a frame-section retaining or lock-post, as will be clearly evident.

As shown in Fig. 7 of the drawings, the said lock-post or finger, normally, extends into the opening 19 of the spring 17 for the engagement with the frame-section 2 in the

manner usual to bag-frame fasteners of this character, the said lock-post or finger, when the lever is manipulated moving in said opening 19 and also into the opening 15 in 5 the flat top 7 of the main shell or casing, as illustrated in Fig. 8, when the lever is raised.

The outward movement of the said lever is limited by the end-portion 35 of the said lock-post or finger being brought into ar- 10 rested engagement with the under surface-portion of the spring 17 in the manner repre- sented in said Fig. 8 of the drawings.

The operations of the various bag-frame fasteners hereinbefore described will be 15 clearly understood from an inspection of the several figures of the drawings, and any further description of the same is therefore deemed unnecessary.

It will be understood that I have pro- 20 vided a simple, strong and efficient construction, in which I obviate the necessity of riveting the lock-post in place upon the operating lever, and all danger of the lock-post, when the device is in constant use, becoming 25 loose or being dislodged is clearly overcome, and furthermore the manufacture of the construction of the same is greatly simplified, as well as greatly cheapened.

Of course, I am fully aware that changes 30 may be made in the general arrangements and combinations of the several devices and parts, as well as in the details of the construction of the same, without departing from the scope of the present invention as 35 set forth in the foregoing specification and as defined in the clauses of the claims which are appended thereto. Hence, I do not limit my present invention to the exact arrangements and combinations of the several de- 40 vices and parts as described in the said specification, nor do I confine myself to the exact details of the construction of the said parts, as illustrated in the accompanying drawings.

45 I claim:—

1. A bag-frame fastener comprising a main shell having means for securing said shell to a frame-section, said shell being pro- 50 vided with an opening, a locking device piv- otally mounted upon said shell, said locking device consisting of a main member of sub- 55 stantially the same width of said shell and of such length that when closed down upon the top of the shell it will close said open- ing, said member being formed with a dou- ble-under portion, and a lock-post member extending inwardly from the marginal end-

edge of said doubled-under portion, said main member, said doubled-under portion and the said lock-post member all being 60 formed from a single piece of flat sheet steel, said post being movably disposed in the opening of said shell.

2. A bag-frame fastener comprising a main shell having means for securing said 65 shell to a frame-section, said shell being provided with an opening, a locking device pivotally mounted upon said shell, said locking device consisting of a main member of substantially the same width of said shell 70 and of such length that when closed down upon the top of the shell it will close said opening, said member being formed with a doubled-under portion, and a lock-post mem- 75 ber extending inwardly from the marginal end-edge of said doubled-under portion, said main member, said doubled-under portion and the said lock-post member all being formed from a single piece of flat sheet steel, said post being movably disposed in the 80 opening of said shell, and a spring-engaging lug also extending from said main member, combined with a spring secured within said shell, said spring having a portion in en- 85 gagement with said lug and having an open- ing into and through which the said lock- post extends and is normally disposed therein.

3. A bag-frame fastener comprising a main shell having means for securing said 90 shell to a frame-section, said shell being pro- vided in its top with open portions, bearing- 95 portions extending outwardly from said top, a pintle extending across one of said open portions, said pintle having its end-portions mounted in said bearing-portions, and a locking device mounted upon said pintle, said locking device consisting of a manipu- 100 lating lever mounted above the other open portion in said shell, and having a rear- wardly extending portion bent under the main portion of said lever, and a lock-post forming a part of and integrally connected with said bent-under portion, said post be- 105 ing movably disposed in the opening of said shell.

In testimony that I claim the invention set forth above I have hereunto set my hand this 28th day of November, 1917.

JOSEPH S. ISIDOR.
